(57) **CLAIM**

The ornamental design for an animal collar, as shown and described.

DESCRIPTION

FIG. 1 is a perspective view of my new animal collar design;
FIG. 2 is a front elevational view thereof;

FIG. 3 is a left side view thereof;

FIG. 4 is a right side view thereof;

FIG. 5 is a top plan view thereof; and,

FIG. 6 is a bottom plan thereof.

The broken lines showing of a retainer and loop are for
illustrative purposes only and form no part of the claimed
design.
